UNITED STATES PATENT OFFICE.

MATTHEW S. CUMNER, OF BROOKLYN, NEW YORK, AND FREDERICK W. GEISSENHAINER, OF FREEHOLD, NEW JERSEY.

GRINDING MACHINE.

Application filed December 31, 1920. Serial No. 434,194.

To all whom it may concern:

Be it known that we, MATTHEW S. CUMNER, a citizen of the United States of America, and a resident of Brooklyn, in the county of Kings and State of New York, and FREDERICK W. GEISSENHAINER, a citizen of the United States of America, and a resident of Freehold, Monmouth County, and State of New Jersey, have invented certain new and useful Improvements in Grinding Machines, of which the following is a specification, reference being had to the accompanying drawings, forming a part thereof.

Our invention relates to new and useful improvements in cutting and grinding machines and its object is to provide a simple, substantial and satisfactory machine by means of which hobs may be easily and quickly cut with a high degree of accuracy by an abrasive wheel or wheels or other rotary cutting tool.

It is an object of our invention to provide a machine which may also be used for grinding threads or screws with a high degree of accuracy.

A further object is to provide a machine in which the causes of inaccuracy in mechanisms of this type as have been known heretofore, shall be eliminated, so that hobs or screws ground thereon may approach perfection. A machine embodying this invention may therefore be employed and is adapted to be employed in the making of master hobs or screws or hardened master gauges.

Another object of this invention is to provide a machine of the character described in which the parts may be readily controlled, manipulated and adjusted and in which re- placements may readily be made if and as desired.

With the foregoing and other objects in view, which will be apparent to one skilled in the art as the description proceeds, our invention resides in the combination and arrangement of parts and in the details of construction described in the following specification and particularly pointed out in the claims appended hereto, one embodiment of said invention being illustrated in the accompanying drawings. It is to be understood, however, that we do not limit ourselves to the precise embodiment disclosed

herewith as changes can be made within the scope of what is claimed without departing from the spirit of the invention. We intend no limitations other than those imposed by the claims.

Referring to the drawings:

Figure 1 is a front elevational view of a grinder embodying our invention.

Figure 2 is an end elevational view of the machine illustrated in Figure 1.

Figure 3 is a fragmentary rear elevation, partly in section.

Figure 4 is a plan view of the machine of Figure 1.

Figure 5 is a transverse sectional elevation just forward of the carriage on the line 5—5 of Figure 4.

Figure 6 is a longitudinal section through the head or driving portion of the machine.

Figure 7 is an elevational longitudinal section through the axis of the headstock on the line 7—7 of Figure 4.

Figure 8 is a transverse vertical section through the rear of the head stock on the line 8—8 of Figure 7.

Figure 9 is a horizontal transverse section through the driving mechanism on the line 9—9 of Figure 12.

Figure 10 is a horizontal transverse section on the line 10—10 of Fig. 12.

Figure 11 is a plan view of the machine of Fig. 1, partly in section.

Figure 12 is a vertical transverse section through the driving spindle on the line 12—12 of Fig. 6.

Figure 13 is a partial vertical transverse section of the actuating gear box on the line 13—13 of Fig. 6.

Figure 14 is a detail of the automatic reversing mechanism showing a rear vertical longitudinal view partly in section on the line 14—14 of Fig. 12.

Figure 15 is an exploded perspective view of a detail of a clutch assembly.

Figure 16 is a detail sectional view of the line 23—23 of Fig. 11.

Figure 17 is an elevation, in place, of a rotary cutting tool, which may be substituted for the grinding wheel.

Fig. 18 is a horizontal sectional view of the rotary cutting tool block.

Fig. 19 is a horizontal sectional view of a modified form of rotary cutting tool block.

Figure 20 is a plan view of the grinder wheel and a portion of the wheel dressing or trimming mechanism.

Figure 21 is a front elevational view on 5 an enlarged scale of the wheel trimming mechanism.

Figure 22 is a transverse elevational view of the wheel trimming mechanism and adjacent parts.

10 Figure 23 is a transverse sectional elevation taken substantially on line 23—23 of Figure 21.

Figure 24 is a detail sectional elevation of a clamping screw taken substantially on 15 line 24—24 of Figure 22.

Similar reference numerals relate to similar parts throughout the several views.

15 designates the bed of the grinding machine which is preferably supported on legs 20 16 and on a base 17 which comprises a motor compartment accessible through an opening closed by the door 18.

The bed 15 is constructed to form two parallel rails 19 and 20, the former being 25 a V-rail and the latter having a flat surface.

Movable longitudinally on the rails 19 and 20 is a frame 1 to which is attached a bracket 2. The bracket 2 has a nut 3 which 30 fits a screw 4, the nut 3 being affixed to the bracket by bolts 3^a, 3^b (Fig. 8) and thus serving to move the frame 1 as the screw 4 rotates and the nut 3 rides along the screw. The screw 4 is detachably secured 35 to the spindle shaft 46 in any positive way to rotate therewith and on its outer end is held in positive alignment with said shaft by a journal as at 4^a.

40 Adjustably mounted on the frame 1 are transverse tracks 5, 5 on which is slidably carried a transversely operable carriage 6 which may be moved in and out on the tracks 5 by means of a screw 7 operable by a handle 8, the movement of which may be 45 accurately adjusted by reason of a micrometer disc 9. A longitudinal adjustment for the carriage 6 is provided by means of the track 6^a (Fig. 2).

Mounted on the bed 15 is a head stock 50 having a rotating spindle 21 and a face plate 22.

Also mounted on the bed 15 is a tail stock 10 having a dead spindle 11. The tail stock is longitudinally adjustable on 55 auxiliary guides, 15^a, 15^b, and clamped in position by the action of a handle 13. A transverse track 14 provides for a limited transverse adjustment under the action of adjusting screws 12, 12.

60 The carriage 6 carries a driven rotatable grinding wheel 50 for grinding hobs or screws as will be later described in detail. Any other rotatable cutting tool may also be used.

65 It is apparent from the foregoing de-

scription, that a rotation of the screw 4 will actuate the nut 3 and move the bracket 2 with the attached frame 1 and a carriage 6 longitudinally between the spindles 21 and 11. The grinding wheel 50 will move 70 along a gauge or other piece of work held between the spindles 21 and 11, at a rate exactly proportional to the pitch and rotative speed of the screw 4, giving relative movement between the cutting tool and the 75 work. Consequently, supposing the work held in the spindles to be rotating with the exact speed of the screw 4, as will be later set forth in detail, the grinding wheel 50 for example, may by manual transverse actuation, be made to cut a hob or screw having exactly the pitch of the screw 4 but of any desired diameter. By the use of this machine hobs and screws of practically perfect pitch may be ground. The hobs may be, 80 and preferably are, rough cut by usual methods or by the use of a cutting tool 126 (Fig. 17) before being hardened and finished by grinding on this machine.

It is apparent that by the usual well-known expedient of holding the part to be ground in a chuck in place of on the spindle 21, internal hob or screw threads may be ground with the same accuracy.

The screw 4 and the nut 3 are removable 95 and others of various desired pitches may be substituted if other pitches are desired on the gauges or hobs to be ground.

As has been stated, there is a motor compartment in the base 17 in which is, preferably, an electric motor driving a chain 23, which in turn rotates a drive shaft 24 to one end of which a water pump is connected as is usual.

Adjacent the other end of shaft 24 is a 105 worm 25 between the supporting journals 25^a, 25^b. The worm 25 (Figs. 7, 6 and 12) is in mesh with a worm gear 26 on a shaft 30.

Coacting with the worm gear 26 is a clutch having the engaging toothed ends 26^a 110 and 26^b, the former being normally in engagement with a coacting clutch portion of a bevel gear 27 which meshes with a bevel gear 28 affixed to a shaft 29 on which is a series of gears 29^a, 29^b, 29^c adapted to mesh 115 one at a time, selectively with corresponding gears 30^a, 30^b, 30^c slidably affixed to a shaft 30' and operable by the handle or lever 31 as is usual with a set of selective sliding gears to give varying speed of the shaft 30'. 120

Also slidably affixed to the shaft 30' is a gear 33 in mesh with a gear 34, (Fig. 13) both being carried in a frame 32 operable by a handle 35 to bring the gear 34 in mesh with any one of a series of gears 36^a, 36^b, 36^c, 36^d, 36^e, 36^f, affixed to a shaft 36 to which a bevel gear 37 is affixed and in operative mesh with a bevel gear 38 freely mounted on a shaft 39. To the latter shaft is also affixed a bevel gear 40 in mesh with 130

a bevel gear 41 which drives a vertical shaft to the head of which a bevel gear 42 is affixed and is in mesh with the freely mounted bevel gears 43 and 44, rotating them in opposite directions when actuated. Each of these gears 43, 44, has a clutch hub.

A clutch collar 45 keyed or otherwise slidably affixed to the spindle shaft 46 may be thrown into mesh with the clutch hub of either of said gears 43 or 44, and may thus actuate the spindle shaft in either forward or backward direction when the spindle shaft 46 is actuated.

A clutch collar 47 keyed or otherwise slidably affixed to the shaft 39 may be brought into engagement with a clutch hub on the freely mounted gear 38 by a shifting fork 48 on the shift lever 49 which also has forks 49^a, 49^b, to actuate the selective connection either between the worm gear 26 and the bevel gear 27 by reason of the clutch member 26^a or by reason of the clutch member 26^b between a freely mounted reversing gear 51 in operative relation with a gear 52 affixed to the shaft 39.

On the shift lever 49 is a cam member 53 adapted to actuate upwards a lever rod 54 which is spring pressed downwards by a resilient member 55. The rod 54 may actuate the shifting fork 45^a to throw the spindle shaft 46 into engagement with either of the bevel gears 43 or 44, as will be explained.

The rod 54 (Figure 12) is pivoted to a crank 56 which, together with a rocker 57, a sleeve 58 and a short rocker 59 (Fig. 15) are mounted on a rod 60 which may be pushed in and out by a button 61. The sleeve 58 is pinned to the rod 60 and works in and out therewith. On the rear end of the sleeve 58 is a projecting key 58^a adapted to project through a key slot 57^a in the rocker 57 and into a key slot 56^a in the lever 56 when the rod 60 is in its inmost position. A similar but shorter key 58^b projects forward and is adapted to enter a key slot 59^a in the short rocker 59 when the rod 60 is pulled to its outer position. With the rod 60 in its outmost position and the key 59^b projecting forward completely in the short rocker 59, the key 58^a is completely withdrawn from the crank 56 and the rod 54 therefore is detached from engagement with the rocker arm 57 which actuates the clutch 45.

In this outer position of the rod 60 the short rocker is keyed to the rocker 57 and actuates the clutch 45, being itself actuated by a rocker lever 62 in conjunction with an arm 63.

On the frame 1 of the grinding machine (Figure 1) for automatic reversing of the travel are adjustable stops 1^a, 1^b, adapted to contact with pins 64, 64^a (Figure 14) which are slidably mounted in a yoke 64^a and contact with an arm 63 pivoted on shaft

63^a (Figure 12) and having a rearwardly projecting pin 65. A rocker lever 62 pivoted as on a shaft 62^a has a yoke end 62^b into which the pin 65 projects. At the other end of the rocker 62 is mounted a beveled edge latch 66 normally in engagement with a spring pressed snap latch 66^a. The end of the arm 63 projects into the yoke of the short rocker arm 59.

The operation of this mechanism is as follows. When the frame 1 of the machine reaches either desired extremity of its travel a stop 1^a strikes a pin 64 and continued travel serves to press the pin forward to rock the arm 63 which, by reason of the pin 65 taking in the yoke end of the lever 62 moves the lever 62 slightly so that the beveled edge of the latch 66 rides by the edge of the snap latch 66^a.

The latch 66^a being suddenly released snaps forward and rocks the lever 62 and thus the arm 63 over to its extreme throw, actuating the short rocker 59 and through it the sleeve 58 and the rocker 57 and throwing the clutch 45 to the other one of the gears 43 and 44.

From the foregoing description it is seen that a motor may actuate the shaft 24 through the belt 23 and in turn through the worm 25 actuate the worm gear 26. If the clutch 26^a is then in engagement with the bevel 27 the shaft 29 is actuated. Any one of the gear reductions between shafts 29 and 30 may be selected by the operation of the handle 31 and the shaft 30 driven at the desired speed. A further selection of speed may be made between the shafts 30 and 36 by the actuation of the handle 35 thus operating the bevel gear 37 and through it the bevel 38.

With the shift rod 49 over to hold the clutch 26^a in engagement with the clutch of gear 27, the finger 48 will hold the clutch 47 in mesh with the clutch of gear 38 and the shaft 39 will rotate, the gear 40 affixed thereto will actuate the gear 41 and thus the gear 42 and the gears 43 and 44.

By reason of the extreme position of shift lever 49 the cam 53 is in an extreme position such that the rod 54 will be downwardly depressed by the spring 55 and the clutch 45 will be in mesh with the clutch of gear 44 driving the spindle shaft 46 and thus the spindle 21 in forward cutting direction.

Actuation of the shift lever 49 to the other extremity as shown in Figure 12 will release the clutch 26^a and the gear 26 will drive the gear 51 through clutch 26^b and with the "step-up" gear ratio indicated will drive shaft 39 at a high speed through gear 52 and, as before, drive the spindle gears 43, 44 through gear 40 and the intermediate gears and shafts. In this case, however, the rod 54 is raised by the cam 53 and the

clutch 45 will be actuated by the gear 43 to drive the spindle shaft in a reverse direction.

It is essential in the above described operation that the button 61 be fully pressed in so that the rod 54 actuating the crank 56 will be connected by the key 58^a to the rocker arm 57 and thus actuate the clutch 45.

The shifting of the arm 49, (Figure 7) 10 may be manually made by the operator through the crank 49^a, the shaft 49^b, a crank 49^c connected by a rod 49^d, a crank 49^e Figure 6 and a shaft 49^f which is operable by a reverse shift handle 49^g (Figure 9).

15 It is apparent, therefor, that the reversing of the direction of rotation of the spindle shaft may be done manually by the handle 49^g through the rod 54 or automatically by the stops 1^a, 1^b, as described. Automatic reversal of direction, being done by mere shifting of the clutch 45 through the stops 1^a, 1^b, will result in the same speed of rotation of the spindle in both directions, as the gears 43 and 44 are alike and 25 grinding may take place in both directions of travel of the frame 1.

Manual reversal or change of direction, as described, by means of the shift lever 49 may mean a higher reverse travel than the 30 forward travel, owing to the large gear ratio between the gears 51 and 52. A quick return travel of the frame 1 may therefore be made, if desired, as in the case where cutting is desired only on the forward stroke 35 of the frame 1.

40 Mounted on the spindle shaft 46 is a worm gear 67 constantly in mesh with a worm affixed to a shaft 68 (Fig. 11) on which may be affixed a gear 69 actuating a gear 70 which actuates a coacting gear 71, a shaft 72 and a bevel gear 73. The latter actuates a cooperating bevel gear 74 slidably affixed to a shaft 75 as will be described. At the extremity of the shaft 75 45 is affixed a cam 76 having a follower 77 adjustably mounted on an arm 78 (Fig. 16) which is affixed to the cross carriage 6 and results in pushing the cross carriage transversely with an intermittent motion, a return of the carriage being accomplished by a pair of springs 79.

50 The cam 76 may be replaced, if desired, by one having a different number of actuating surfaces by loosening the nut 76^a and sliding the cam off the shaft. In any longitudinal movement of the carriage 6, the cam 76 and its related parts move therewith by reason of the shaft 75 being adapted to slide in the bevel gear 74.

60 This mechanism is used in the cutting of hobs for the purpose of permitting the grinding wheel to follow the desired contour of the hob teeth which, as is well known, are not completely concentric with 65 the hob axis but are cut back on an arc from

the cutting edge to give radial clearness, the cutting edge not being continuous around the periphery.

As the grinding wheel, under the action of cam 76, approaches the axis of the hob in cutting back for clearance, the width of the groove cut will increase relatively in such a manner as to give side clearance to the cutting edge of the hob tooth as will be apparent to those skilled in the art to which this invention appertains. It is further apparent that the period of movement of the carriage 6 may be regulated by regulation of the speed of shaft 75 and by the number of actuating surfaces on cam 76.

70 In order to provide for cutting those hobs which are of a spiral nature or form it is desirable to continuously and automatically adjust the position of the cam 76 to correspond with the angle of the hob teeth desired, thus changing the phase relation between the actuating cam 76 and the hob being cut.

75 This is accomplished by means of a sleeve 74^a (Fig. 3) having a reduced portion 74^b, 80 affixed to the gear 74 and turning therewith. A slot 74^c is cut in the sleeve or collar 74^a at an angle to the axis of said sleeve.

85 Affixed to shaft 75 is a pin 75^a which rides in the slot 74^c forming the driving means 85 between gear 74 and shaft 75.

90 As has been explained, the movement of the frame 1 to which carriage 6 is affixed moves the shaft 75 slidably through the sleeve 74^a and the gear 74. This action results in pin 75^a riding along slot 74^c in such a manner as to gradually turn shaft 75^a phase increment in addition to the rotative action of gear 74, sleeve 74^a being held from longitudinal movement by abutting a bearing against the shaft 75 journal box.

95 It is apparent that the angle of slot 74^c must correspond to the angle of the hob spiral cutting teeth edge and sleeves of various desired angles may be substituted for the particular one shown in the drawings.

100 The casing enclosing gears 69, 70, and 71 may be removed as by loosening a latch button 80, whereupon other ratio of gears 105 may be manually placed on the shaft 68, the stud 70^a and, if required, on the shaft 72. Preferably and usually, however, the gear 69 is the only one that is changed, the pinion 70 (Figure 7) being mounted on a 110 stud 70^a slidably affixed in the arm 70^b which may be swung about its support, in this case the journal of the shaft 68. Thus any gear, within limits, may be used in place of the gear 69 shown, if of the correct pitch, 115 and gear 70 adjusted to mesh between it and the gear 71 on the shaft 72.

120 Thus, by manual change of gears, the speed of the shaft 75 may be varied.

125 The carriage 6 comprises a mounting for 130

a shaft 50^a on which the grinder wheel 50 is affixed and is rotated at the desired speed by means of a driving belt (not shown) from an auxiliary driving motor (not shown) applied to a belt pulley 81.

The journals 50^b, 50^b of the shaft 50^a are mounted as by clamping fingers 82, 82, pivotally positioned as by the studs 83, 83 and clamped over the journals as by the 10 bolts 84, 84, taking in threaded holes in the lower stationary clamping fingers 85, 85.

The fingers of one of said pairs of clamping fingers, (as for example the left hand pair in Fig. 20) may both be pivotally mounted as at 83 on the arcuate frame 90. The other of said pair of clamping fingers (as for example the right hand pair in Fig. 20) is slidably adjustable in and out transversely between the guiding members 86, 20 86 (Figs. 22 and 24) and may be clamped in position by the nuts 87, 87. The purpose of this adjustment is to align the axis of the grinding wheel with the axis of the rotating piece to be cut or at any desired 25 angle thereto.

The frame 90, carrying the journals in which the shaft 50^a revolves, is mounted on arcuate guides 88 and may be adjusted about a horizontal transverse axis passing 30 through the center point of the cutting wheel. This adjustment is made by a screw 91, being itself held from longitudinal movement by a stud 91^a taking in a groove 91^b in the shank of the screw. The thread 91^c of the screw meshes with a thread cut on 35 the arcuate periphery of the frame 90.

A bolt 89 whose head rides in an arcuate slot in the frame 90 may be clamped by reason of the nut 89^a and frictionally hold 40 the frame 90 in set position.

The purpose of this adjustment is to incline the cutting wheel 50 as desired for the purpose of cutting very steep pitch hobs.

A longitudinal adjustment of the grinding 45 wheel relatively to the carriage 6 may be obtained by reason of the guides 92 and the clamping screws 93, 93.

A transverse movement of the carriage 6 by reason of the screw 7 has already been 50 described.

One of the essentials to the grinding of perfect threads on hobs is that the cutting surfaces of the grinding wheel be in good condition always and at an angle corresponding 55 with the angle between the sides of the finished thread. It is essential also, when steep pitch hobs are cut as by turning the grinding wheel at an angle about a horizontal axis, that the sides of the cutting 60 wheel be properly trimmed to the proper angle with due allowance for the position of the wheel. To insure this we have devised a wheel trimmer which is illustrated in preferred embodiment particularly in Figures 65 20-24 inclusive.

The trimmer mechanism is mounted in conjunction with the grinding wheel on the same base and moves with the wheel in transverse, arcuate and longitudinal adjustments so that it is ready at all positions to 70 be used in trimming the wheel.

The details of construction of the trimmers and the various adjustments in the operation thereof are all described in a co-pending divisional application Serial No. 75 566,906 and these details therefore will not be further described in this application.

When it is desirable to use a milling cutter for roughing work previous to grinding, a form of device as shown in Figs. 17, 18, 80 19, may be provided.

A shaft 127 (Figs. 7 and 18) is driven from the main shaft through a change speed gearing 128, a shaft 129, bevel gears 130, a shaft 131, a gear 132 and a gear 133 85 slidably affixed to shaft 127 which has a longitudinal movement by reason of the travel of the frame 1. The rotative speed of shaft 127 is therefore changeable by reason of the gear set 128.

A worm or spiral gear 134 on shaft 127 drives a cooperating gear 135 which by means of bevel gears 136, 137, 138, and co-acting shafts 136^a, 137^a, 138^a, actuates a cutter shaft 139 having affixed thereto a 95 cutting tool, as, for example, a milling cutter.

In the modification of Fig. 19, gear 135, through shaft 136^b, spiral gears 136^a, shaft 137^b, and spiral gears 138^b, actuates the 100 cutter shaft 139^b and the rotary cutter 126.

To provide for feeding the cutter in and out transversely, the slideable shaft 127 is preferably divided and a universal joint affixed therein (Fig. 17).

To provide for accurate adjustment of the cutting tool, a cradle 141 is provided in which milling cutter block 142 rests and is adjustably held by clamping screws 143, 143, taking in arcuate grooves 144, 144, in the 110 block. The block or head is arcuately adjustable about the transverse center line of the cutter which intersects the line of head and tail centers of the machine. A scale graduation is provided on the head and 115 cradle to aid in setting the cutter.

It is apparent that the movement of the frame 1 longitudinally over the bed of the lathe will move the grinding wheel 50 or the rotary cutter 126 back and forth over the surface of the work to be finished, the pitch being determined by the pitch of the screw 4 and its coacting nut 3. The cutting tool, therefore, requires no other motion of itself than the proper transverse and arcuate 120 adjustments previously mentioned and a rotative motion imparted to it through the shaft 127.

The speed of the rotating part to be ground is widely adjustable in the device 130

as illustrated, giving a choice of six positions of the lever 25 for each of the three speeds set by the lever 31 or a total of eighteen possible forward or reverse cutting speeds as well as the quick return speed operated by the lever 49^g.

What we claim is:—

1. In a grinding machine of the character described, a rotatable shaft, means for attaching thereto a piece to be ground, a plurality of means for reversing the direction of rotation of said shaft, a frame, means to move said frame parallel to said shaft in either direction, a grinding wheel operatively affixed to said frame and means to rotate said grinding wheel, said reversing means comprising an automatic reversing mechanism actuated by the movement of the frame and a manually actuated reversing mechanism, said manually actuated reversing mechanism comprising means for increasing the speed of movement of said frame when traveling in the reverse direction.
2. In a grinding machine of the character described, a rotatable shaft, means for attaching thereto a piece to be ground, a plurality of means for reversing the direction of rotation of said shaft, a frame, means to move said frame parallel to said shaft in either direction, a grinding wheel operatively affixed to said frame and means to rotate said grinding wheel, said reversing means comprising an automatic reversing mechanism actuated by the movement of the frame and a manually actuated reversing mechanism, said manually actuated reversing mechanism including means for selectively engaging either of said reversing means.
3. A grinding machine comprising a motor, a rotary shaft, means for attaching thereto a piece to be ground, gearing between said motor and said shaft for driving the shaft at different speeds, manual means for controlling the driving gearing, reversing gearing in operable relation to the shaft, a slidable frame guided to move parallel to the shaft, operable means between said shaft and said frame whereby the rotation of said shaft moves said frame, means on said frame for controlling said reversing gearing, other reversing gearing, manual means for controlling said other reversing gearing, a grinding wheel, and an adjustable support for said wheel affixed to said slidable frame.
4. In a grinding machine, a rotary shaft, means for attaching thereto a piece to be ground, a slidable frame, a grinding wheel, a support for said wheel affixed to said slidable frame, means to move said frame at an exact predetermined speed with relation to the speed of said shaft, means to reverse the direction of travel of said frame actuated by said frame, means to guide said

frame parallel to said shaft, an arcuate adjustment for said wheel support, a transverse adjustment for said wheel support, and a longitudinal adjustment for said wheel support.

5. In a device of the character described, a motor, a rotatable shaft, means for attaching thereto a piece to be ground, a slid-
70 able frame, means to guide said frame, means affixed to said frame coacting with means affixed to said shaft whereby the rotation of said shaft slidably moves said frame in positive speed relation to the speed of said shaft, an operable connection between said motor and said shaft to rotate said shaft comprising a plurality of gears, a plurality of means for controlling the speed relation between said gears, means actuated by said frame to reverse the direction of rotation of said shaft, a grinding wheel adjustably mounted on said frame and means to rotate said wheel.

6. In a grinding machine of the character described, a motor, a rotary shaft operatively connected thereto, means for attaching to said shaft a piece to be ground, a frame, means to move said frame parallel to said shaft in either direction, a grinding wheel operatively affixed to said frame, means to rotate said grinding wheel transversely of the frame, and operative connections between said rotary shaft and said reciprocating means including a gear operatively connected with the rotary shaft, a plurality of gears coacting with said gear, a shaft actuated by one of said plurality of gears and slidably therein, a cam actuated by said shaft and removably affixed thereto, a follower for said cam adapted and arranged to reciprocate the grinding wheel and means to adjust the follower.

7. In a grinding machine of the character described, a motor, a rotary shaft operatively connected thereto, means for attaching to said shaft a piece to be ground, a frame, means to move said frame parallel to said shaft in either direction, a grinding wheel operatively affixed to said frame, means to rotate said grinding wheel, means to periodically reciprocate said grinding wheel transversely of said frame, and means to vary the periodicity of reciprocation of said grinding wheel.

8. In a grinding machine of the character described, a motor, a rotary shaft operatively connected thereto, means for attaching to said shaft a piece to be ground, a frame, means to move said frame parallel to said shaft in either direction, a grinding wheel operatively affixed to said frame, means to rotate said grinding wheel, means to periodically reciprocate said grinding wheel transversely of said frame, and a plurality of means to vary the periodicity of reciprocation of said grinding wheel com-

prising a cam, a plurality of actuating means on the cam and means to vary the speed of the cam.

9. In a grinding machine of the character described a rotary shaft, a source of power for said shaft, a frame, means to slidably move said frame parallel to said shaft in positive speed relation to the speed of said shaft, a grinding wheel, a support for said wheel slidably affixed to said frame, means to periodically reciprocate said grinding wheel support in positive time relation to the rotation of said shaft, and means to vary the amplitude of reciprocation of said

15 grinding wheel support.

10. In a device of the character described a rotatable shaft, means for attaching thereto a piece to be shaped, a rotary cutting tool, means to rotate said tool, an operable 20 connection between said shaft and said tool whereby relative longitudinal motion is obtained between the piece to be shaped and the cutting tool, means including a cam, to periodically reciprocate said tool transversely of the axis of said shaft and means 25 to vary the phase relation between the relative angular position of said cam and the piece to be shaped.

11. In a grinding machine, work holding 30 means, means for rotating said work holding means, a tool holding frame, means for moving said frame longitudinally with respect to the work holding means, means for moving said tool holding frame transversely 35 with respect to the work holding means and means for changing the phase relation between the longitudinal and transverse movement of said tool holding frame.

12. In a machine, rotary work holding 40 means, means for rotating said work holding means, a tool holding frame, means to move said frame longitudinally of said work holding means in either direction, means for reciprocating said frame transversely 45 of the work holding means and means set in operation by the longitudinal movement in operation by the longitudinal movement of the tool holding means for controlling the reciprocation of the frame.

13. In a machine, rotary work holding 50 means, means for rotating said work holding means, a tool holding frame, means to move said frame longitudinally of said work holding means in either direction, means for reciprocating said frame transversely of the 55 work holding means and means set in operation by the longitudinal movement of the tool holding means for controlling the recip-

ocation of the frame by changing the phase relation of the reciprocating and longitudinal movement of the tool holding frame.

14. In a machine, rotary work holding means, means for rotating said work holding means, a tool holding frame, means to move said frame longitudinally of said work holding means in either direction, means including a cam for reciprocating said frame transversely of the work holding means and means set in operation by the longitudinal movement of the tool holding means for controlling the rotation of the cam and the reciprocation of the frame.

15. In a machine of the character described, rotary work holding means, a frame, means to move the frame parallel to the axis of the work holding means in either direction, tool holding means on said frame, means to periodically reciprocate said frame and means to vary the periodicity of reciprocation of said frame.

16. In a machine of the character described, a work holding frame, a tool holding frame, means including operatively connected driving members for reciprocating said second frame transversely of said first frame, means for moving the second frame longitudinally of the first frame, and means controlled by the movement of the second frame longitudinally of the first frame for varying the periodicity of the transverse reciprocation of the second frame.

17. In a machine of the character described, a work holding frame, a tool holding frame, means including operatively connected driving members for reciprocating said second frame transversely of said first frame, means for moving the second frame longitudinally of the first frame, and means controlled by the movement of the second frame longitudinally of the first frame for causing relative movement between said driving members and varying the periodicity of the transverse reciprocation of the second frame.

18. In a device of the character described, a shaft, a grinding wheel carried thereby, 105 supporting means for the shaft and means for adjusting the shaft longitudinally, angularly about one end and arcuately about the center point of the wheel.

In testimony whereof we hereunto affix 110 our signatures.

MATTHEW S. CUMNER.
FREDERICK W. GEISSENHAINER.
